CLAIM

The ornamental design for a lamp lens, as shown and described.

DESCRIPTION

FIG. 1 is a perspective view of the lamp lens as mounted to a flashlight;

FIG. 2 is a front elevational view of the lamp lens;

FIG. 3 is a back elevational view of the lamp lens;

FIG. 4 is a side elevational view of the lamp lens, the opposite side of which is an identical mirror image;

FIG. 5 is a top plan view of the lamp lens; and,

FIG. 6 is a bottom plan view of the lamp lens.

The broken lines shown on the drawings are for illustrative purposes only and form no part of the claimed design.
